UNITED STATES PATENT OFFICE.

ROBERT H. BERKSTRESSER, OF YORK, PENNSYLVANIA, ASSIGNOR TO
CORNELIUS M. FULTON, OF SAME PLACE.

CHECKREIN-HOOK.

SPECIFICATION forming part of Letters Patent No. 653,194, dated July 3, 1900.

Application filed May 9, 1899. Serial No. 716,082. (No model.)

To all whom it may concern:

Be it known that I, ROBERT H. BERKSTRESSER, a citizen of the United States, residing at York, in the county of York and State of Pennsylvania, have invented certain new and useful Improvements in Checkrein-Hooks for Harness, of which the following is a specification, reference being had therein to the accompanying drawings.

10 My invention relates to checkrein-hooks for harness; and its object is to provide a device of this character which will permit a ready engagement of the checkrein therewith and effectually prevent an accidental disengagement of the rein.

15 The novel features of the device will be fully described hereinafter and defined in the appended claim, in connection with the accompanying drawings, in which—

20 Figure 1 is a view in perspective of a checkrein-hook embodying the invention, and Fig. 2 is a central vertical section of the same.

25 The reference-numeral 1 designates a base or frame cast in a single piece and having an integral loop 2 at its rear end. I preferably form this frame with downwardly-curved sides 3 and an upwardly-curved and rounded rear end 4 to give the ornamental appearance of a miniature saddle, although of course this 30 specific contour is not essential.

35 5 designates the hook proper, the lower end of which extends under the front end of the base or frame, where it is secured by a bolt 6, passing through the frame and hook, as shown, and secured by a nut 7. The upper end or head 8 of the bolt is provided with integral parallel lugs or ears 9, between which is pivotally secured an angle-lever 10, the pivotal support being located at the angle of the 40 lever. The short arm 11 of this lever 10 is curved forwardly and adapted to contact with the under side of the rearwardly-extending curved arm 12 of the hook. The long arm 13 of the angle-lever terminates in a head or 45 enlargement 14, which serves as a weight to normally hold the short arm 11 against the hook, and thus prevent the checkrein after its engagement with the hook from slipping out.

It will be clear from the drawings that the checkrein can be easily slipped into the hook, 50 the angle-lever tilting upon its pivotal support for this purpose. As soon as the rein passes the short arm of the lever the weighted arm of said lever returns it to its normal position, thus closing the hook and preventing 55 the slipping out of the rein until the angle-lever is again tilted by hand.

I deem it important that the curved arm 12 of the hook extend over the angle-lever, as shown, to such an extent that the weighted 60 end 14 thereof will strike the under side of said hook-arm when the rein is inserted, so as to stop the downward movement of the short arm of said lever and prevent the same from being thrown downward to such an extent as to throw the weighted arm beyond the 65 center of gravity, so that as soon as the rein has passed the free end of the short arm the weighted arm will immediately return the angle-lever to its normal position. 70

I claim—

The improved checkrein-hook herein described, comprising a base or frame, a hook having one end extended beneath said frame and its other end extended over the same, a 75 vertically-disposed bolt passed through the frame and having upon its lower end a nut bearing upon the under side of the lower portion of the hook and provided at its upper end with ears, and an angle-lever pivotally mounted between said ears with a normally vertically disposed curved short arm engaging the under side of the upper portion of the hook, and its longer arm weighted and disposed beneath said upper portion of the hook and 85 adapted to contact therewith to limit the downward movement of the curved short arm of the lever, all substantially as herein shown and described.

In testimony whereof I affix my signature 90 in presence of two witnesses.

ROBERT H. BERKSTRESSER.
